DISAPPEARING STAIRWAY

Wilbert C. Pfahl, Silver Lake, Ohio

Application June 1, 1946, Serial No. 673,795

2 Claims. (Cl. 228—50)

1

This invention relates to disappearing stairways of the ceiling or overhead floor type.

Heretofore, stairways of this type have been manufactured in which a panel was hinged at one end of an overhead floor opening with a stair structure extensibly and retractably mounted on the panel, and with spring-wound drums and cables provided for separately counter-balancing the panel and stair structure. Great difficulty has been encountered in the past, however, in that when the spring drums became out of order the customer could not remove the same without substantially completely dismounting the entire stairway structure, which then remained out of service while repairs were being made. Another serious difficulty arose in that the customer usually possessed insufficient skill or equipment for setting requisite counter-balancing tensions in the drums.

One object of the invention is to provide apparatus of the character described including improved means for effectively mounting spring-wound counter-balancing drums, which may be easily removed for repairs, adjustments or replacements, without disturbing the manual operation of the stairway.

Another object of the invention is to provide in apparatus of the character described, improved spring-drum mountings adapted to be supplied in separate removable units, with the spring drums therein set with requisite tensions and ready for attachment of the operating cables thereof, whereby no special skill or equipment is required to detach or assemble the spring-drums in the apparatus.

Other objects of the invention will be manifest from the following brief description and the accompanying drawings.

Of the accompanying drawings:

Figure 1 is a top plan view, partly broken away, illustrating a disappearing stairway embodying the features of the invention.

Figure 2 is a vertical cross-section through the apparatus, taken substantially on the line 2—2 of Figure 1.

Figure 3 is a fragmentary top plan view, on an enlarged scale, taken at the left of Figure 1.

Figure 4 is a cross-section, on the same scale, taken on the line 4—4 of Figure 3.

Figure 5 is a similar cross-section taken on the line 5—5 of Figure 3.

Figure 6 is an enlarged top plan view, showing the apparatus in dismounted condition.

Figure 7 is an enlarged side elevation of the apparatus in dismounted condition.

Referring to the drawings, the numeral 10 designates an overhead floor structure, having therein a rectangular opening 11 at one end of which is hinged a closure panel 12. Secured to one end jamb of opening 11, above the hinge

2

point of the panel, is a bracket 13 having thereon spaced inwardly projecting lugs 14, 14, on which is pivoted a frame 15 including opposite elongated guide strips 16, 16, for sliding engagement in opposite guide slots 17, 17 along the outer faces of stringers 18, 18 of stair structure 19. Adjacent the free end of panel 12, at opposite sides thereof, is mounted a pair of lugs 20, 20 on which elongated guide blocks 21, 21 are pivoted to be slidable in said guide slots 17. Thus, the stair structure 19 is slidable on the guide strips 16 and guide blocks 21, toward and from a retracted position (not shown) upwardly through opening 11. Releasable latching devices of known type, are provided at the lower ends of the stringers, as indicated at 22, and on the lugs 20, for releasably locking the stairway when moved toward retracted position. By means of the equipment so far described the stairway is manually operable toward and from said retracted position thereof.

For facilitating effortless operation of the stairway toward and from retracted position, removable and replaceable spring-winding units 23, 23 may be provided at each side of the opening 11, in spaces provided between the opposite stringers 18 and adjacent side jambs 24, 24. The units 23 may include L-shaped brackets each having side and end plates or legs 25 and 26 for suitable releasable attachment as by means of screws, against the corresponding side and end jamb faces at the hinge end corners of opening 11. To provide additional rigid support for the units angular lug extensions 25a and 26a are provided on the side and end plates thereof for attachment, as by means of screws, to the upper floor surface. Integral with the side plate 25 of each unit 23 may be horizontally spaced, open-ended tubular stems 27 and 28, extending freely laterally inwardly and being received through central apertures of panel and stairway counter-balancing spring drums 29 and 30, respectively. The drums are hollow, and have flat springs 31 and 32, respectively, hooked at one end through slots in outer cable-winding peripheral portions of the drums, the inner ends of the wound springs being similarly hooked through slots 33 and 34 extending from the open ends of the tubular stems 27 and 28. Cotter pins 35 and 36 prevent accidental removal of the drums from the stems thereof.

Attached to the winding peripheral portion of each panel counter-balancing drum 29, may be a flexible cable 37, which extends over a pulley 38 (see Figure 2) attached to the side jamb 24 adjacent the other end of opening 11, the other end 55 of the cable extending downwardly and being slidably adjustably attached to suitable attaching means 40 on the panel. This sliding attachment is of known type adapted to facilitate operation of a stop member 41 on the cable for limiting 60 downward pivotal movement of the panel and

also to prevent accidental unwinding of the cable 37 during shipment or repair (see Figures 6 and 7).

The stair-structure counter-balancing drum 30 of each unit 23 is located downwardly and inwardly of the adjacent drum 29, and has attached to the outer winding peripheral portion thereof one end of a flexible cable 42, the other end of which is attached to a lug 43 on the outer face of stringer 18 intermediate the ends thereof (see Figure 2).

The springs of the drums 29 and 30 are set with desired tensions when placed on the respective stems thereof, in such a manner as to provide requisite spring tension to counter-balance the closure panel and stair-structure. This preferably is such that in the extended position of the stairway the spring action is slightly overbalanced by the weight of the stairway so that it will stay in downwardly extended condition, as best shown in Figure 2, but will require only relatively slight effort to operate it toward retracted position. The spring tension of the panel drums on the other hand, is relatively weaker so that the panel will not slam closed to cause loosening of the hardware thereof.

The operation of the improved stairway structure, either with or without the spring counter-balancing means, has been clearly described above. It will be readily seen, however, that the apparatus is adapted to be completely installed without requiring any substantially high degree of skill, and particularly with reference to assembly and attachment of the spring counter-balancing units 23. Similarly, should the counter-balancing devices require repairs or adjustments, it is only necessary to detach the extended outer ends of cables 37 and 42, remove the units with drums 29 and 30 retained thereon, and ship the same to the manufacturer or servicing agent. When the units have been repaired or adjusted, and returned, it is only necessary to mount them in the opening 11 as before and attach said extended outer ends of the cables, no spring adjustments being required by the owner or customer, because the units may be furnished with the springs properly set by means of special equipment, and with the cables properly retained in wound condition on the drums. For the last mentioned purpose, it will be readily seen by reference to Figures 6 and 7, that upon release of each cable 37 with respect to the stair structure 19 and pulley 38, the stop member 41 will engage between the plate 26 and the outer peripheral portion of drum 29, thereby preventing any unwinding and also permitting presetting of the tension as previously set forth.

It is understood that the advantages of removability and interchangeability of the units 23 may be utilized also with single spring-winding drums thereon. Other modifications of the invention may be resorted to without departing from the spirit thereof or the scope of the appended claims.

What is claimed is:

1. A disappearing stairway for an opening in an overhead floor structure, comprising a closure panel hinged at one end of said opening, guide means adjacent the other end of said opening of the floor structure at opposite sides thereof, a stair structure, stair-mounting means for mounting said stair structure to be extensible and retractable on the upper side of said panel, said stair structure being substantially narrower than said opening to provide spaces at opposite sides thereof, separate drum-mounting units including

brackets removably secured independently of said stair-mounting means to said floor structure at opposite sides of said opening adjacent the hinged end of said panel and thereby being adapted to be installed or removed without disturbing the use of said stair structure as such, opposite pairs of fixed stems on each of said separate brackets, said stems extending from the said brackets freely into said spaces at opposite sides of the stair structure, opposite pairs of spring-wound panel and stair structure counter-balancing drums rotatably received on said stems of the brackets, releasable means for retaining said drums on said stems, flexible elements connected between said opposite panel drums and said panel and guided by said guide means for counter-balancing said panel, and flexible elements connected between said opposite stair structure drums and the stair structure for counter-balancing the same, said drum-mounting units and the respective flexible elements of the drums thereof including attaching means for affixing the flexible elements relatively of the unit and thereby to limit spring-winding of the drums when the flexible elements are released from the respective structures operated thereby.

2. A disappearing stairway for an opening in an overhead floor structure, comprising a closure panel hinged at one end of said opening, guide means in said floor opening, a stair structure including opposite side stringers, stair-mounting means for mounting said stair structure and said panel whereby the stair structure is extensible and retractable on said panel, a separate drum-mounting unit including a bracket removably secured independently of said stair-mounting means to said floor structure at the hinged end of said panel and thereby being adapted to be installed or removed without disturbing the use of said stair structure as such, fixed stems on said bracket extending freely outwardly thereof, separate spring-wound panel and stair structure counter-balancing drums, said drums being centrally apertured to be rotatably received on said fixed stems, releasable means for retaining said drums on said stems, means on said drums and on said stems for setting predetermined spring-wound tension in the drums for a retracted position of the panel and stair structure, flexible elements connected between said panel drum and said panel and guided by said guide pulley means for counter-balancing the panel, and flexible elements connected between said stair structure drum and the stair structure for counter-balancing the same, said drum-mounting unit and the respective flexible elements of the drums thereof including releasably interengaging portions for affixing the flexible elements relatively of the unit and thereby to limit spring-winding of the drums when the flexible elements are released from the respective structures operated thereby.
